UNITED STATES PATENT OFFICE

2,479,198

TELEPHONE INSTRUMENT

George Thomas Baker, Liverpool, England, assignor to Automatic Electric Laboratories Inc., Chicago, Ill., a corporation of Delaware

Application May 27, 1944, Serial No. 537,629
In Great Britain July 19, 1943

2 Claims. (Cl. 179—100)

1

The present invention relates to telephone instruments whether of the type suitable for connection to public exchanges or of the type for use with small private exchanges, which may be of a simpler nature owing to the possibility of dispensing with some of the more usual parts. The main object of the invention is to produce a construction which while being more pleasing to the eye is arranged so that the various parts are normally protected from dust and dirt and possible damage.

According to one feature of the invention, in a telephone instrument of the handset type the handset is arranged to fit into and substantially close the mouth of a depression in a member which serves for its support and protection.

According to another feature of the invention, in a telephone instrument of the handset type the handset and its support are so shaped that the handset when placed on its support is substantially within the support and forms a smooth continuation of the outer surface of the support.

A further feature of the invention is that in a telephone instrument of the handset type including a dial switch, the dial switch is located in a recess the mouth of which is substantially closed by the handset when not in use.

Preferably the instrument is constructed so that its outside surface is formed of a small number of smooth curves and may for instance be roughly a prolate hemispheroid. The handset portion, that is to say the portion including the transmitter 10 and receiver 11 which is held against the speaker's face while the telephone is in use, forms a kind of lid or plug for a container, or base 12 with the transmitter and receiver housings 10 and 11 mounted on the lower surface of member 15 so that when replaced on the container to constitute the complete instrument they are protected from dust and dirt. With this construction it is possible to give the instrument clean lines since the various components such as transmitter 10, receiver 11 and dial switch 13 are all located inside the opening 14 of the main body, or base 12, of the instrument when it is not in use.

In these circumstances the handset need not be of the conventional shape though obviously of course it must still conform to the recognised dimensions which have been found most suitable for the average size of face. The transmitter 10 and receiver 11 may be connected together by a substantially flat member 15 suitable for forming part of the main casing when the handset is

in its normal position, this member 15 incorporating a suitable handle 16 or grip by which the handset may be removed from the instrument and held during use in conversation. The handle member 16 however will preferably not stand out but will continue the lines of the remainder of the instrument, the required handle effect being produced by a cavity or an opening 17 between two depressions in the handle 16 and member 15. The handset may if desired carry on its inside surface a card (not shown) or the like suitable for the reception of frequently used numbers or instructions appropriate for the local network.

15 In order to ensure that the handset shall take up its proper position even if it is restored somewhat carelessly, it may be desirable to provide the opening 14 with an inclined or substantially conical seating so that it will tend to fall into proper position and give a substantially dust-tight closure. Part of the conical portion of the instrument would be movable or would include a movable plunger (not shown) so that the handset could operate so-called switchhook springs for the usual purpose, or alternatively the handset might incorporate a gravity switch for producing the necessary circuit changes.

The handset cord (not shown) could be attached in the usual manner but preferably it will be attached to the inside of the instrument and to the inner side of the handset so that when the instrument is not in use the handset cord will be entirely enclosed. Conveniently this cord may be of the retractile type so that no special care

35 on the part of the user is necessary to ensure that it returns to its proper position without impeding the correct seating of the handset. With this arrangement it might be desirable, in order to avoid possible trouble with the cord, to arrange

40 for the handset portion to be sloped towards the user, the slope preferably being that normally employed for the dial switch. There would then be a greater tendency for the user automatically to replace the handset always in the same position, i. e. with the transmitter at the lower end nearer the user. Alternatively, the slope of the opening 14 could be of a similar amount in a transverse direction. The opening 14 and the corresponding handset member may also be shaped so as not to be symmetrical about more than one axis in which case the handset must always be replaced the same way.

The usual components, such as induction coil, bell and dial switch 13 will be located inside the 55 instrument and the base 12 which will probably

be provided with rubber feet in accordance with usual practice may conveniently be formed with a grill or louvres in order to enable the bell to be heard satisfactorily. The dial switch 13 will preferably be immediately beneath the handset so that it can readily be operated when the handset is removed. Such an arrangement has the additional advantage that dialling cannot be attempted without the removal of the handset. A disinfectant or antiseptic pad (not shown) might also be mounted inside the instrument and would be effective for long periods in view of the normally closed interior.

Since with the arrangement according to the invention the working parts are now completely enclosed it would be possible for the casing to be made of such shape and colour as to harmonise with any particular decorative scheme desired by the user and alternatively the handle member 16 by which the handset is removed instead of being substantially flush could be of some special ornamental nature.

It will be understood that the instrument as a whole would preferably be provided with some means for gripping it readily so as to enable it to be moved, or a locking device could be provided so that an attempt to remove the handset would lift the whole instrument, for instance the handset might fit into place with a type of bayonet connection. As a further development the instrument might be built into a wall or table so as to form a substantially flush surface, the removal of the handset for speaking purposes giving access to the dial.

The accompanying drawings Figs. 1-3, show the general appearance of one possible construction, Fig. 1 being a view of the handset member, Fig. 2 of the remainder of the instrument and Fig. 3 of the complete instrument when not in use.

According to the invention, therefore, a telephone instrument has been produced which offers important advantages over conventional construction both in appearance and in more satisfactory operation.

What I claim as new and desire to secure by Letters Patent is:

1. In a telephone desk set having a hand telephone comprising an elongated member having oval-shaped ends, a curved handle integrally connected to the upper surface of said member near said oval-shaped ends, an opening between said handle and the upper surface of said member to provide a hand grasp for the user, the lower sur-

face of said member being flat, a pair of housings for a telephone transmitter and a telephone receiver extending beyond said member, a base conforming in shape to said member having a smaller but similarly shaped opening for receiving both said housings, an upper flat edge of said base cooperating with the outer rim of said lower flat surface of said member when said member is placed on said base for closing said base opening, and a calling device including a rotatably operated finger wheel located within said base opening in between the space occupied by said housings and protected against accumulation of dust by said member when said member is placed on said base to cover said base opening.

2. In a telephone desk set having a hand telephone comprising an elongated member having oval shaped ends, an upper surface, a curved handle integrally connected to said upper surface of said member near both ends of said member, a flat lower surface, and a pair of housings for a telephone transmitter and a telephone receiver extending beyond said lower flat surface of said member, a base conforming in shape to said member having a large single opening for receiving both said housings, and an upper flat edge encircling said single opening of said base cooperating with the outer rim of a portion of said flat lower surface of said member when said hand telephone is placed on said base for closing said opening to prevent accumulation of dust in said opening while said member is supported on said base.

GEORGE THOMAS BAKER.
